[57] CLAIM

The ornamental design for a beverage cooler, as shown and
described.

DESCRIPTION

FIG. 1 is a top, front, right side perspective view of a
beverage cooler showing my new design;

FIG. 2 is a top plan view thereof;

FIG. 3 is a bottom plan view thereof;

FIG. 4 is a side elevation view thereof;

FIG. 5 is a cross-sectional view taken along line 5—5 of
FIG. 2;FIG. 6 is an exploded top, front, right side perspective view
thereof;FIG. 7 is a front elevation view of FIG. 6, the opposite side
being a mirror image;FIG. 8 is a cross-sectional view taken along line 8—8 of
FIG. 7;FIG. 9 is a top, front, right side perspective view of an
alternate embodiment of FIG. 1;FIG. 10 is a front elevation view of FIG. 9, the opposite side
being a mirror image;FIG. 11 is a right side elevation view of FIG. 9, the opposite
side being a mirror image;

FIG. 12 is a top plan view of FIG. 9;

FIG. 13 is a bottom plan view of FIG. 9; and,

FIG. 14 is a cross-sectional view taken along line 14—14 of
FIG. 12.The broken line showing of the wording is for illustrative
purposes only and forms no part of the claimed design.
